GOTTDANK L. KOTHNY, OF STRAFFORD, PENNSYLVANIA, ASSIGNOR TO C. H. WHEELER MANUFACTURING COMPANY, OF PHILADELPHIA, PENNSYLVANIA, A CORPORATION OF PENNSYLVANIA.

EJECTOR CONTROL

Application filed June 30, 1925. Serial No. 40,515.

My invention relates to a system of control for ejector apparatus utilized for raising the pressure of elastic fluid, and more particularly for producing and maintaining various degrees of vacuum in the condenser of a steam power plant, in an evaporator, vacuum pan, de-aerator, and, in general, wherever sub-atmospheric pressure is to be procured or maintained.

10 In accordance with my invention, in a system utilizing two or more ejectors in series or tandem, with or without interstage condensing means, there is effected automatic control of delivery of motive fluid, as steam,

15 to one or more stages in response to changes in degree of vacuum or absolute pressure in the condenser or other chamber to be evacuated or in the suction chamber or chambers of one or more of the ejectors of the series.

20 More particularly in accordance with my invention, the delivery of motive fluid to an ejector of a series is automatically reduced or discontinued in response to rise to predetermined magnitude of the absolute pressure 25 in the suction chamber of that ejector or of an ejector in a later stage of the series of ejectors.

My invention resides in an ejector control system of the character hereinafter described and claimed.

30 For an understanding of my invention and for an illustration of several of the various forms it may take, reference is to be had to the accompanying drawings, in which:

35 Fig. 1 is a curve sheet illustrating the operating characteristics of a multi-stage ejector and of one of the ejectors operating alone.

40 Fig. 2 is a curve sheet illustrating the operating characteristics when there is utilized an interstage condenser.

Fig. 3 is a vertical sectional view, partly 45 in elevation, illustrating a system embodying my invention.

Fig. 4 is a vertical sectional view, partly 50 in elevation, illustrating a modified embodiment of my invention.

Fig. 5 is an elevational view of a further 55 form my invention may take.

Fig. 6 is a sectional view, partly in elevation, of valve structure utilizable in my system.

Fig. 7 is a sectional view, partly in eleva-

tion, of a modified form of valve structure utilizable in my system.

55 Referring to Fig. 1, the curve A represents the operating characteristic of a two stage ejector, without interstage condenser, ordinates being pounds of free air per hour compressed by both stages operating cumulatively, and abscissæ being absolute pressures, in inches of mercury.

With both stages in operation, the total consumption of motive fluid or steam for both stages is, for example, 500 pounds per 60 hour.

Curve B is the operating characteristic for the second stage ejector operating alone, in which case the total motive fluid or steam consumption is, for example, 375 pounds per 65 hour. It will be noted that the characteristic 70 curves A and B intersect or cross each other at X, which signifies that for maintaining high vacuum, as, for example, 29 inches of mercury absolute, the two ejectors operating cumulatively are necessary, for when the second stage ejector operates alone, as when no steam or motive fluid is delivered to the first stage ejector, the lowest absolute pressure is between 3 and 4 inches mercury ab-

75 solute. To procure the higher vacuum, both ejectors operate and consume about 500 pounds of steam per hour. But beyond the point X, on curve A, that is, for first stage suction pressures upwards of about 5 inches mercury absolute, the second stage ejector operating alone, as indicated by curve B, removes and compresses more air than do the two stages together, and more than this, with the second stage ejector operating alone, the 80 total steam consumption is reduced to about 375 pounds per hour.

85 Accordingly, Fig. 1 illustrates that for first stage suction pressures, in excess of about 5 inches absolute, it is more economical to shut off the first stage ejector and operate the second stage ejector alone, for not only is more air removed and compressed, but the work is accomplished with less motive steam.

90 In Fig. 2 the curves A and B represent the operating characteristics for both stages and for the second stage alone, when utilizing an interstage condenser. In this case the point 95 of intersection X lies in the neighborhood of, for example, six inches mercury absolute,

from which it follows that it is more economical when the first stage suction pressure attains the order of 6 inches absolute, the second stage shall operate alone, with less steam consumption, to remove and compress greater amounts of air.

Obviously, as the first stage suction pressure rises, in the case of both Fig. 1 and Fig. 2, with both ejectors operating, the second stage suction pressure also rises, and therefore, for the purposes of my invention hereinafter described, the automatic control may be in response to either the absolute pressure obtaining in the suction chamber of that ejector whose operation is to be discontinued, or the absolute pressure obtaining in the suction chamber of a later stage.

It will be understood that Figs. 1 and 2 are merely illustrative, and are not limitative 20 of my invention, which is applicable as well to ejectors having different characteristics and utilizing other quantities of motive fluid or steam.

It will further be understood that my invention is applicable to multi-stage ejector 25 systems whatever may be the type or character of the ejectors utilized in the several stages.

Referring to Fig. 3, E^1 is a first stage 30 ejector whose suction chamber a connects with the condenser or other chamber from which air is to be removed and compressed, for example, to atmospheric pressure, for maintaining in the condenser or chamber a a 35 suitably low absolute pressure or suitably high vacuum. The ejector E^1 comprises the motive-fluid-expanding nozzle structure N^1 and the diffuser structure D^1 , as well understood in the art. The diffuser D^1 discharges 40 into the suction chamber b of the second stage ejector E^2 , which in the example illustrated is of the radial or disk jet type whose motive-fluid-expanding nozzle structure is indicated at N^2 and whose diffuser structure 45 is indicated at D^2 , the latter discharging into the discharge passage or casing c having a discharge port at d , delivering to atmosphere, or to any suitable region at, above or below atmospheric pressure. Motive fluid steam is delivered at any suitable pressure 50 from any suitable source through the pipe e controlled by the valve f , from which steam is delivered to the nozzle structure N^2 of the second stage ejector E^2 . Steam is also delivered through the manually operated valve g and pipe h to the automatic 55 valve structure V , through which the motive steam is delivered, when the valve V is open, to the nozzle structure N^1 of the first stage ejector E^1 . The valve structure is of any suitable character or type, responsive 60 to changes in absolute pressure in the suction chamber a of the first stage ejector, to which chamber a is made the suction pipe connection i . The control of the mechanism

of the valve V is made such that when the absolute pressure in the chamber a rises to a predetermined magnitude, such, for example, as corresponds with point X , Fig. 1, or about 5 inches mercury absolute, the valve 70 V closes, thereby discontinuing delivery of motive steam to the nozzle structure N^1 of the first stage ejector E^1 , thereby automatically converting the two stage ejectors into a single stage ejector in which the second 75 stage ejector E^2 only continues to operate, thereby in effect changing from operating characteristic A to operating characteristic B. Similarly, if the absolute pressure in the chamber a should thereafter fall to a 80 point below a predetermined magnitude, as, for example, to a point to the left of the point X , Fig. 1, or to an absolute pressure suitably less than 5 inches mercury absolute, 85 the valve V will open, causing both ejectors to operate cumulatively, and thereby return to operating characteristic A.

Referring to Fig. 4, the first stage ejector E^1 discharges into the interstage condenser I , in which the motive steam or condensable component of the discharge mixture is condensed, and the air and uncondensed vapors passed to the suction chamber b of the second stage ejector E^2 , which in this example 90 is a tubular ejector.

In this case the motive steam delivered to the nozzle structure N^1 of the first stage ejector E^1 is again controlled by the automatic valve V , whose suction connection i in this example connects with the second 100 stage suction chamber b , whereby when the absolute pressure in the first stage suction chamber a rises to a point, as X , Fig. 2, corresponding with about 6 inches absolute pressure, the delivery of steam to the first stage nozzle structure N^1 is discontinued; and the system is transferred from operating characteristic A to characteristic B, 105 Fig. 2.

It will be understood, however, that the connection of the suction pipe i to the second stage suction chamber b is merely by way of example, and that in Fig. 4 the connection i may be made to the suction chamber a , or that in Fig. 3 the suction connection i may be made to the suction chamber b of the second stage ejector E^2 .

In general, however, it is preferred to make the suction connection i to the suction chamber of that ejector whose motive steam supply is to be reduced or discontinued.

In Fig. 5 there are shown three ejectors E^1 , E^2 and E^3 in series or tandem, with interstage condensers I and I^1 and with an after condenser I^2 . Whether or not the condensers I , I^1 and I^2 are utilized, or whether any one or two of them be omitted, the steam to the nozzle structure of the ejector E^1 is controlled by valve V in response to changes in absolute pressure in the suction chamber 115 120 125 130

5 *a* of the first stage ejector; similarly, the supply of steam to the nozzle structure of the second stage ejector *E*² is effected through the similar automatic valve *V*¹, whose suction pipe *i* is connected to the suction chamber *b* of the second stage ejector *E*².

10 In this system it is apparent that a plurality of ejectors will be cut out of service automatically, either simultaneously or in succession, in response to rise of the absolute pressures in their suction chambers to predetermined different magnitudes.

15 Referring to Fig. 6, there is illustrated a form of valve mechanism utilizable for controlling the delivery of steam to the nozzle structure of one or more stages, as described in connection with Figs. 3, 4 and 5. The inlet *e* is connected to the boiler or other 20 source of motive fluid or steam under suitable pressure, and the port *j* connects with the nozzle structure of the ejector which is to be automatically cut into or out of service. The valve member *v* is pressed towards 25 its seat *v*¹ by a spring *k*, and when in the position illustrated delivery of steam to the nozzle structure of the associated ejector is discontinued. A flexible or yielding dia- 30 phragm *m* has applied thereto the upward pull of the spring *s*, whose tension is adjustable by the adjusting screw *n*; and the under side of the diaphragm *m* is subjected to the vacuum or absolute pressure obtaining 35 in the suction chamber of the associated ejector, the suction pipe *i* communicating with the space beneath the diaphragm *m*. The diaphragm *m* is attached to the pilot 40 valve *o* which, when the absolute pressure in the chamber below the diaphragm *m* rises to a predetermined magnitude, is raised against its seat, thereby shutting off communication between the steam passage *p* and the cylinder or chamber *q*, in which is movable the piston *r* connected to the valve *v*. 45 In consequence, pressure upon the top of the piston *r* is discontinued and the spring *k* closes the valve *v*, shutting off steam from the nozzle structure of the ejector. When 50 the absolute pressure in the suction chamber of the ejector is below a predetermined magnitude, the pilot valve *o* opens in opposition to spring *s*, allowing steam to flow from port *e* through the passage *p*, pilot valve *o* to the chamber *q*, causing steam pressure 55 to be exerted upon the top of the piston *r*, which then opens the valve *v* in opposition to the spring *k*, causing the delivery of steam to the nozzle structure of the ejector.

60 In Fig. 7 a generally similar arrangement is shown, except in this case the suction pipe *i* is in part formed of a vertical column having at its bottom the U-bend *t*, in which is disposed mercury or the like, filling the chamber beneath the diaphragm *m*, which, 65 in this case, is normally thrust downward-

ly by the adjustable spring *s*. In this case, when the absolute pressure in the suction chamber of the ejector rises to a predetermined magnitude, the pressure of the mercury on the under side of the diaphragm *m* increases, causing closure of the pilot valve *o* in opposition to spring *s*; similarly, when the absolute pressure in the suction chamber of the ejector decreases below a predetermined magnitude, the pressure exerted by the spring *s* upon the diaphragm *m* exceeds that of the mercury, the pilot valve *l* opens, causing valve *v* to open, with consequent delivery of steam to the nozzle structure of the ejector.

70 It will be understood that the valve structures of Figs. 6 and 7 may be utilized, or that any other suitable valve structure may be employed, operable, however, under the control of the absolute pressure in the suc- 75

80 tion chamber of an ejector.

85 It will therefore be understood that my invention is not limited to the structure or character of the valve structure utilized.

90 It will further be understood that while I have herein referred to absolute pressures in the suction chamber of an ejector, such reference has been utilized for brevity, for it will be understood that the suction connection which controls the valve structure may be made to any other suitable part of the apparatus or system so long as the valve control is effected in correspondence with the absolute pressure in the suction chamber of the ejector or any correlated pipe or chamber, to effect a control of the character herein described.

95 100 In the two stage ejectors hereinbefore referred to, when both are operating, with or without interstage condenser, it is preferred that the total throat area of the nozzle structure of the first stage with respect to the total throat area of the nozzle structure of the second stage shall be such that the ratio of compression in the first stage 105 is greater than the ratio of compression in the second stage, for all first stage suction pressures within a range below about 5 inches mercury absolute, as described in Letters Patent No. 1,283,593, November 5, 1918.

110 115 What I claim is:

120 125 1 The method of comprising elastic fluid in stages, which comprises entraining and raising the pressure of elastic fluid in each of successive stages by elastic motive fluid in each stage, substantially completely discontinuing application of elastic motive fluid in an earlier of said stages by the motive fluid in response to rise to predetermined magnitude of the suction pressure in said earlier stage, whereby in continuing the operation a greater weight of elastic fluid is compressed per unit of elastic motive fluid utilized.

130 2. The method of compressing elastic

fluid in two stages to substantially atmospheric pressure, which comprises entraining and raising the pressure of the elastic fluid in each stage by elastic motive fluid in each stage, and completely discontinuing application of elastic motive fluid in the first stage by utilizing the pressure of said motive fluid in response to rise of the suction pressure in said first stage to a magnitude of the order of five inches mercury absolute, whereby in continuing the operation by the second stage a greater weight of elastic fluid is compressed per unit of elastic motive fluid supplied to the second stage.

3. The method of compressing elastic fluid in two stages to substantially atmospheric pressure, which comprises entraining and raising the pressure of the elastic fluid in each stage by the elastic motive fluid in each stage, between stages condensing the condensable component of the discharge of the first stage, and substantially completely discontinuing application of elastic motive fluid in the first stage in response to rise of the suction pressure in said first stage to a magnitude in excess of approximately six inches mercury absolute.

4. The combination with a plurality of injectors in staged relation, of means responsive to rise of suction pressure in a stage other than the last stage for discontinuing delivery of motive fluid to said stage, whereby upon continued operation of the other stage or stages a greater weight of elastic fluid is compressed per unit of elastic motive fluid supplied to the other stage or stages.

5. The combination with two stage ejector apparatus for raising elastic fluid to substantially atmospheric pressure, of means for discontinuing delivery of motive fluid to one of said stages when the suction pressure of the first stage rises to the order of 5 inches mercury absolute, whereby upon continued operation of the second stage a greater weight of elastic fluid is compressed per unit of elastic motive fluid supplied to the second stage.

6. The combination with two stage ejector

apparatus for raising elastic fluid to substantially atmospheric pressure, the ratio of compression of the first stage being greater than the ratio of compression of the second stage for all first stage suction pressures less than about 5 inches mercury absolute, of means responsive to rise of first stage suction pressure to the order of 5 inches mercury absolute for discontinuing delivery of motive fluid to said first stage, whereby upon continued operation of the second stage a greater weight of elastic fluid is compressed per unit of elastic motor fluid supplied to the second stage.

7. The combination with two stage ejector apparatus for raising elastic fluid to substantially atmospheric pressure, of an inter-stage condenser, and means responsive to rise of first stage suction pressure to a magnitude in excess of about six inches mercury absolute for discontinuing delivery of motive fluid to said first stage, whereby upon continued operation of the second stage a greater weight of elastic fluid is compressed per unit of elastic motive fluid supplied to the second stage.

8. The combination with a plurality of injectors in staged relation, of a valve through which elastic motive fluid is supplied to the motive-fluid-expanding nozzle structures of said injectors, and a valve intervening between said valve and the nozzle structure of one of said injectors constituting a stage preceding another of said injectors, said second named valve responding automatically to open when the suction pressure of the injector with which it is associated decreases to a predetermined magnitude, whereby upon opening said first named valve motive fluid is supplied to the nozzle structure of said other of said injectors until the suction pressure of said one of said injectors decreases to said predetermined magnitude, whereupon said second named valve opens and motive fluid is delivered through said first and second named valves to effect co-operation of said injectors.

GOTTDANK L. KOTHNY.

CERTIFICATE OF CORRECTION.

Patent No. 1,666,141.

Granted April 17, 1928, to

GOTTDANK L. KOTHNY.

It is hereby certified that error appears in the printed specification of the above numbered patent requiring correction as follows: Page 2, line 19, for the misspelled word "illuustrative" read "illustrative", and line 74, for the word "ejectors" read "ejector"; page 3, line 117, claim 1, for the word "comprising" read "compressing" and line 120, for the misspelled word "successve" read "successve"; page 4, claim 5, end of line 43, insert the numeral 5, and line 62, claim 6, for "motor" read "motive"; and that the said Letters Patent should be read with these corrections therein that the same may conform to the record of the case in the Patent Office.

Signed and sealed this 29th day of May, A. D. 1928.
